UNITED STATES PATENT OFFICE

ERIK AUGUST FORSBERG, OF STOCKHOLM, SWEDEN, ASSIGNOR TO THE DE LAVAL SEPARATOR COMPANY, OF NEW YORK, N. Y., A CORPORATION OF NEW JERSEY

PULSATATOR FOR MILKING MACHINES

Application filed May 3, 1928, Serial No. 274,803, and in Sweden November 4, 1927.

The object of this invention is to provide a milking machine pulsator adapted to have a constant pulsation speed and maximum working reliability. Constructions intended to accomplish these purposes are known and one devised by me and set forth in an application Serial No. 259,875, filed by me in the United States Patent Office March 7, 1928, and in Sweden a year earlier is effective to so regulate the speed and is reliably operative under normal working conditions. Under unfavorable working conditions, however, disturbances may occur, mainly because small quantities of moist air may enter the brake cylinder and condense in the overflow channel. While the present invention embodies the basic conception of the earlier application, it is an improvement thereon in that it avoids any construction which can give rise to the above mentioned condition. It has also additional advantages which will be clear from the following description.

Several different embodiments of the invention are shown in the drawings, in which

Fig. 1 is a longitudinal sectional view of a pneumatic milking machine pulsator embodying my invention.

Fig. 2 is a similar view of part of a modified pulsator.

Fig. 3 is a side elevation showing a modified connection between the working piston or diaphragm and the valve for regulating the pneumatic pulsations to the milking organ.

Fig. 4 is a view, similar to Fig. 3 of another modification.

Fig. 5 is a side elevation of a part of a pulsator modified by the substitution of a different type of pneumatic braking device.

Referring first to the construction shown in Fig. 1:

In Fig. 1, A is the "operating cylinder" in which is arranged a "working piston," which in this construction takes the form of a dia-

phragm or membrane B, which can be made of leather, caoutchouc, corrugated metal, or any other suitable material. The chambers C and D on opposite sides of membrane B are, by means of channels E and F, connected to a valve chest G in which a valve H moves. Valve chest G is, by way of example, connected with a source of vacuum through a connection I. To membrane B is fixed a rod J acting on valve H by means of a cross piece K and stops M and N provided on valve rod L. To the valve runs a channel O, which connects with the atmosphere.

Rod J is also connected to a piston P, which moves in a cylinder R, whose inner end is connected, through a passage Q, with the vacuum system. Between its ends cylinder R has a nozzle S, to which is connectible a tube S' adapted for connection to the teat cups either directly or through a secondary pulsator, which in known manner effects the distribution of air in the teat cups.

Rod J is also connected to another diaphragm or membrane T, which forms one flexible wall of a chamber U. Chamber U communicates with a chamber X through a narrow, preferably regulable hole V in a wall Y separating the two chambers. Rod J passes through wall Y and is at its end provided with recesses Z and near membrane T with recesses W, so that, at the end positions of the rod J, a free passage is obtained between the chambers U and X.

The pulsator works in the following way.

In Fig. 1, the parts are shown in the position they occupy at that moment when the stroke to the left is just completed. Cross piece K has come into contact with stop M and has moved slide valve H over to the left side. Thereby chamber D has been connected with vacuum through channel F, valve chest G and connection I; while chamber C has been connected with atmosphere through channels E and O. By reason of the difference in pressure between the chambers C and

D, membrane B and rod J are now moved to the right. During the first part of the stroke, the movement takes place rather easily, as air can pass rather freely through recesses Z from chamber U to chamber X. When the movement has proceeded for a comparatively short part of the stroke, the recessed end of rod J moves beyond wall Y and rod J tightens more or less completely against wall Y. A certain compression of the air in chamber U now takes place, and the movement cannot now proceed more rapidly than is permitted by the restricted flow of air from chamber U to chamber X through the small holes V. In this manner the speed of movement is regulated. When the stroke to the right is nearly completed, recesses W reach wall Y, whereby a comparatively free passage for air is again opened between the chambers U and X. Equalization in pressure in the two chambers now takes place and piston J completes its stroke comparatively rapidly. As piston rod J nears the end of its stroke to the right, cross piece K engages projection N and, as rod J completes its movement, moves slide valve H to the right hand end position opposite that shown in the drawings. The parts B, J and T now move to the left, the operation being similar to that which occurred in the described movement of these parts to the right.

Approximately or exactly when rod J passes its middle position, piston P also passes connection S, thereby causing the latter to shift its connection from vacuum to atmospheric pressure, or vice versa. In this way, pulsations in the teat cups or in the secondary pulsator are generated.

A feature which especially characterizes the present invention is that chambers U and X together form an entirely closed system, and therefore impurities cannot, in any circumstances, penetrate from outside and obstruct the flow of air through opening V. For this purpose a single-acting membrane is used in the braking device, whereby no movable tightening against the outer atmosphere around rod J is necessary.

In the embodiment shown in the accompanying drawing there exists, however, such a tightening around rod J at the operating cylinder. This is of minor importance, since, without considerable complication of the construction, it is in any case not possible wholly to hinder moist air and the like from penetrating into the operating cylinder, and, moreover, this does not substantially affect the efficiency of the pulsator.

However, to guard against the possibility that a certain friction may occur by reason of tightening around the rod J which, in unfavorable circumstances, could cause irregularities in the operation, a single-acting "operating cylinder", of which that shown in Fig. 2 is an example, may be used. In this

construction, membrane 10 is normally kept extended by a spring 11 and is brought to the opposite end position under the influence of a vacuum in the chamber 12. Other details may be similar to those in Fig. 1, but the cylinder R with attached parts should be located between the operating and brake cylinders.

A certain difficulty may arise due to the known quality of membranes to permit only a rather limited length of stroke compared with their dimensions. Thus, it may be difficult, at least with certain dimensions, to give the recesses Z and W sufficient dimensions to insure a rapid equalization in pressure between the chambers U and X at the end positions of the stroke. This may be avoided by arranging, in the wall Y, a special valve which is opened at the end positions by the rod J. But another and greater inconvenience is that piston P, and especially slide valve H, in order to function in a reliable way, may require a movement of greater length than a membrane T of suitable diameter will permit. In such a case it is practicable to arrange gearing between rod J and piston P and valve rod L which will increase the amplitude. Such a gearing can be of any known kind, for instance, a lever or a toothed wheel. Figs. 3 and 4 show schematically two different embodiments of such a device.

In Fig. 3, rod J is connected with piston P by means of a lever 20 pivoted at 21. The ends of the lever 20 are forked to embrace pins 22 on rod J and pins 23 on piston rod P. The end of lever 20 works against the stops M and N on slide valve rod L. The interior of the cylinder R may be connected with the vacuum system through the connection 24.

In the embodiment shown in Fig. 4, the rod J is provided with a rack engaging with a pinion 30, which is connected to a larger toothed wheel 31, which in turn engages a rack 32 on the piston rod of piston P, the piston rod carrying the cross piece K adapted to engage stops M and N.

In order to increase the mobility of one or both membranes B and T, it is practicable to make one or both of them in the form of bellows, as shown in Fig. 5. This device is especially suitable as a substitute for membrane T, because it may be constructed of such dimensions as to be responsive to small pressure differences. In such a case, however, the volume of air rushing to and from the chamber U is comparatively large, and therefore the chamber X must be given ample dimensions if strong differences in the pressure are not to occur. It is therefore desirable in this case to provide chamber X with a movable wall against the exterior, so that the volume of this chamber can change without the pressure therein deviating from the atmospheric pressure to any noteworthy degree. If it is desired to use the simple form

of membrane in the operating cylinder, which is practicable because of the comparatively great difference in pressure which prevails in it, which difference in an ordinary embodiment would amount to about 0.5 atmosphere, the amplitude will, of course, become rather limited. In such a case it is practicable to arrange, between the operating and brake cylinders, a gearing which increases the movement.

Fig. 5 shows schematically such a device. 40 is the piston rod extending from the operating cylinder, which may be provided with a double or single-acting membrane or piston. 45 The piston rod is provided with a rack engaging a pinion 41, on whose shaft is a toothed wheel 42. This toothed wheel engages a rack on a rod 43, which carries the end head 44 of a bellows-membrane 45. An 50 expandible and contractible chamber 48 is formed by a flexible wall 47 secured to the other end head 46 (sleeved on rod 43) of the bellows-membrane.

Having now fully described my invention, 55 what I claim and desire to protect by Letters Patent is:

1. A milking machine pulsator comprising a pneumatically operable working member, a pneumatic pulsation tube, means controlled 60 by said member to effect pneumatic pulsations in said tube, and a fluid braking device connected with, operable by, and controlling the speed of, said working member; said braking device comprising walls forming two 65 chambers shut off from the atmosphere, the exterior wall of one of said chambers comprising a movable diaphragm, and ports affording communication between said chambers.

2. A milking machine pulsator comprising a pneumatically operable working member, a pneumatic pulsation tube, means controlled 70 by said member to effect pneumatic pulsations in said tube, and a fluid braking device connected with, operable by, and controlling the speed of, said working member; said braking device comprising walls forming two chambers shut off from the atmosphere and ports affording communication between said chambers, the exterior walls or both of said chambers comprising movable diaphragms.

3. A milking machine pulsator comprising a pneumatically operable working member, a valve adapted to control the pneumatic operation of said working member, means controlled 75 by said member to actuate the valve, a tube through which pneumatic pulsations are transmissible, a regulating valve, connected with and actuatable by said working member, adapted to effect pneumatic pulsations in said tube, and a fluid braking device connected with, operable by, and controlling the speed of said working member; said braking device comprising walls forming chambers shut off 80 from the atmosphere and ports affording

communication between said chambers, the exterior wall of one of said chambers comprising a movable diaphragm.

4. A milking machine pulsator comprising a pneumatically operable working member, a pneumatic pulsation tube, means controlled 85 by said member to effect pneumatic pulsations in said tube, and a braking device connected with, operable by, and controlling the speed of, said working member; said braking device comprising walls forming two chambers shut off from the atmosphere, said pneumatically operable working member and an exterior wall of one of the chambers comprising 90 movable diaphragms connected to operate in unison.

5. A milking machine pulsator comprising a pneumatically operable working member, a valve adapted to control the pneumatic operation of said working member, means controlled by said member to actuate the valve, a tube through which pneumatic pulsations are transmissible, a regulating valve connected with and actuatable by said working member, adapted to effect pneumatic pulsations in 95 said tube, and a braking device connected with, operable by, and controlling the speed of, said working member; said working member and said braking device comprising respectively expandible membranes connected to operate in unison.

6. A milking machine pulsator comprising a pneumatic pulsation tube, a pulsating device, means controlled by the pulsating device to effect pneumatic pulsations in said 100 tube, and a fluid braking device connected with, operable by, and controlling the speed of the pulsation device; said pulsating device comprising a rigid wall and a diaphragm forming between them a pulsation chamber, the exterior wall of the diaphragm being constantly open to atmospheric pressure, a valve adapted to vary the absolute air pressure in said chamber, and means actuatable by said diaphragm to actuate said valve.

7. A milking machine pulsator comprising a pneumatically operable working member, a pneumatic pulsation tube, means controlled by said member to effect pneumatic pulsations in said tube, a rod reciprocable by said working member, a fluid braking device comprising walls forming two chambers into which said rod extends, and a diaphragm operable by said rod and forming one of said walls, and means allowing, during the movement of said rod and diaphragm, flow of fluid between said chambers at such rate as to regulate the speed of the working member.

8. A milking machine pulsator comprising a pneumatically operable working member, a pneumatic pulsation tube, means controlled by said member to effect pneumatic pulsations in said tube, a rod reciprocable by said working member, a fluid braking device comprising walls forming two chambers into

which said rod extends, and a diaphragm operable by said rod and forming one of said walls, a port in the wall separating said chambers allowing restricted flow of fluid, said rod having grooves adapted to afford additional fluid communication between said chambers as the rod approaches the ends of its movement.

In testimony of which invention, I have hereunto set my hand, at Stockholm, Sweden, on this 19th day of April, 1928.

ERIK AUGUST FORSBERG.
